UNITED STATES PATENT OFFICE.

LOUIS W. DILLON, OF NORTH ATTLEBOROUGH, ASSIGNOR OF ONE-HALF TO
HOMER M. DAGGETT, JR., OF ATTLEBOROUGH, MASSACHUSETTS.

ELECTRIC-LAMP FIXTURE AND SWITCH.

SPECIFICATION forming part of Letters Patent No. 399,134, dated March 5, 1889.

Application filed August 7, 1888. Serial No. 282,190. (No model.)

To all whom it may concern:

Be it known that I, LOUIS W. DILLON, of North Attleborough, county of Bristol, State of Massachusetts, have invented an Improvement in Electric-Lamp Fixtures and Switches, of which the following description, in connection with the accompanying drawings, is a specification, like letters on the drawings representing like parts.

10 My invention relates to an electric-lamp fixture adapted to be supported on the ceiling of a room or in other locality not of easy access, the said fixture being provided with a switch for controlling the circuit of the lamp, which 15 switch is arranged to be operated from a point some distance from it, and is so constructed as to complete its movement automatically from the open to the closed position, or the reverse, so that it is impossible to leave the 20 switch in the position to make an imperfect contact, thus endangering the destruction of a greater or less portion of the apparatus by the heat produced by the resistance to the current of an imperfect contact. A switch of 25 this kind is especially useful for controlling a circuit supplied by a current of high potential—such as employed for operating incandescent lamps arranged in series or for arc lamps—the fixture being shown in this instance as provided with an incandescent lamp.

The fixture comprises a base of wood or other insulating material provided with binding-posts or connectors for the current-supplying conductors and with a switch controlling a direct connection between the said binding-posts. The base is also provided with a 35 tubular shank or stem, which may be of wrought-iron pipe, and supports at its extremity a lamp-socket of usual construction, adapted to receive an incandescent lamp in the usual manner. The movable member of said switch consists of a pivoted arm having an angular movement on its pivot between two stops, one of which constitutes an anvil or 40 operating contact-member for the switch-arm, which is acted upon by a spring connected with said arm in advance of its pivot, and also connected with a pivot at the rear of the switch-pivot and in line with the switch when 45 in an intermediate position between the two stops. The result of this arrangement of the

spring is that the point of connection between the spring and the switch moves concentrically with the switch-pivot, but not with the spring-pivot, in such manner that the spring 55 is strained in passing from either extreme position of the switch toward its intermediate position, and consequently acts by its elastic force to move the switch from the intermediate position to either of its extreme positions. 60 In other words, the switch when in an intermediate position is in a condition of unstable equilibrium under the force of the spring, and if moved slightly beyond said intermediate position will be carried by the spring suddenly and quickly to its extreme position, so that if in opening the switch it is positively moved by the operator beyond the intermediate position its movement will be completed and the switch left wholly open; but if the 70 operator should fail to carry it to the intermediate position it would be promptly returned into engagement with the anvil-piece and make perfect contact therewith, and it is impossible to leave it in a position near to 75 but not making perfect contact with its anvil-piece.

Figure 1 is a side elevation of a lamp-fixture and switch embodying this invention; Fig. 2, a plan view of the base portion of the 80 fixture, as seen looking upward toward the base portion when in its usual position on the ceiling of a room, with the parts below the switch removed; Fig. 3, a plan view of the other side of the base portion; Fig. 4, a sectional detail on line *x*, Fig. 3; and Fig. 5, a sectional detail of the switch and its anvil-piece.

The operative parts are supported on a base, *a*, which may be of wood or other insulating 90 material, and is adapted to be fastened on the ceiling of a room or upon other suitable support, being usually placed in the position shown in Fig. 1. Upon the base *a* are secured the usual binding-posts, *b* *b'*, with which the 95 current-supplying conductors are connected in the usual manner. The said base has fastened upon it a metallic socket, *c*, which is countersunk below the surface of the base *a*, that is fastened to the ceiling or wall, and is 100 provided with a groove, *c'*, in line with the groove *a'* in the said base, extending to the

inner ends of the binding-posts $b b'$, so as to receive conducting-wires $2 3$, that extend from said binding-posts to the lamp-socket. The piece c has a tubular portion, c^2 , extending through the base a and provided with an internal thread in which is secured a tubular shank or stem, d , which may be of wrought-iron pipe, and has fastened upon its lower end a lamp-socket, e , (see Fig. 1,) to receive an incandescent lamp, f , of usual construction, in the usual manner. The wires $2 3$ are provided with insulating-coverings and extend down through the tube d , as shown in Fig. 4, to suitable terminals in the lamp-socket e , and when the lamp is applied thereto connect with the ends of the lamp-filament, thus placing the same in circuit between the binding-posts $b b'$.

When an apparatus of the kind thus far described is arranged in series with other lamps, the lamp f must be extinguished without opening the circuit, in order to leave the other lamps in the circuit in operation, and this is effected by making a direct connection of substantially inappreciable resistance between the binding-posts $b b'$, while opening such connection or shunt for the lamp will cause the entire current to pass through the lamp and set it in operation. Such a shunt for the lamp and means for opening and closing the same are shown as consisting of a switch, g , pivoted at g' on the base a , and connected by wire 4 with one of the binding-posts, as b , the said switch co-operating with an anvil or contact piece, h , also fastened upon the base a , and connected by wire 5 with the other binding-post, b' . The anvil or contact piece h also constitutes a stop that limits the movement of the switch-arm g on its pivot in one direction, and there is a corresponding stop, i , that limits its movement in the other direction, said stop i being supported on the base a and insulated from the circuit-wires.

It is necessary for the safe operation of apparatus working with currents of high potential that a switch should make perfect contact when closed, and its members should be perfectly separated when open, and in order to insure such operation the switch-arm g is, in accordance with the present invention, acted upon by a spring, k , connected at one end with the said switch at k' in front of its pivot g' , and having its other end connected directly or indirectly with a pivot, m , at the rear of the pivot g' of the switch g , and substantially in line with said switch when in intermediate position between its stops $h i$, so that the said spring is strained in the movement of the switch from either stop toward the intermediate position, as will be readily understood from Fig. 2, and consequently tends by its elastic force to throw the switch from the intermediate position in either direction. If, therefore, the switch g is moved a slight distance in either direction from its intermediate position, the spring will automatically throw it promptly the entire dis-

tance until it is arrested by the stop on the side toward which it is moved, and it is impossible to leave the switch near to its co-operating contact h or resting lightly against it, as the spring would always move it from such position into complete and perfect contact with the said contact-stop.

In order to provide for the operation of the switch from a distant point when the fixture is not easily accessible, the switch-arm g is provided with an operating cord or cords, $n n'$, (being shown in this instance as a continuous cord passing through the eye or loop k' on the switch,) with which the spring k is connected, and provided with knots $n^2 n^3$ at either side of said eye and too large to pass through it, so that in effect the cord is the same as two separate cords each fastened at its end to the switch-arm. The said cords $n n'$ extend from the switch-arm at each side and pass over pulleys $l' i'$ (shown in this instance as connected with the stops $h i$) for the switch-arm, and extend therefrom to any point accessible to the operator, who by pulling on the cord n will open the switch, and thus throw the light into operation, or by pulling on the cord n' will close the switch and extinguish the light, and, as before described, the spring k will automatically complete the movement of the switch in either direction after it has been moved by the cord to and slightly beyond the intermediate position, so that the operation of making the contact at the switch is automatic and does not depend upon the manipulation of the operator.

In order to bring the pivots of the switch g and its actuating-spring in proper position with relation to one another, in conjunction with a convenient arrangement of the parts on the base a , as shown in Fig. 2, the axial line of said spring must pass across the lamp-supporting tube d in the movement of the switch, and in order to provide for the movement of the spring it is connected with its pivot m by means of an arm, p , having an opening, p' , through which the tube passes, of sufficient length to admit of the required angular movement of the said arm and spring, as shown in Fig. 2. The tube d and operative parts near the base thereof are shown as enclosed in an ornamental cover or shell, $t t'$, the latter portion having an opening, t^2 , to accommodate the movement of the switch within it, the end of said switch and its operating-cord being outside the said shell.

I claim—

1. The combination of a lamp-fixture comprising a base and lamp-supporting shank fastened thereon, with a switch pivoted on said base and provided with stops, limiting its movement in either direction, a spring connected at one end with said switch in advance of its pivot, and the arm connected with the other end of said spring and pivoted on said base at the other side of the shank from the switch-pivot, and provided with an opening through which said shank passes, and operat-

ing-cords connected with said switch, and pulleys therefor on the base of the lamp-fixture, substantially as described.

2. The combination of the base and lamp-
5 supporting shank extending therefrom, with
a switch pivoted on said base at one side of
said shank, a spring connected with said
switch in advance of its pivot, and the arm
connected with said spring pivoted on said
10 base at the other side of the shank from the

switch-pivot, and provided with an opening
through which the said shank passes, sub-
stantially as and for the purpose described.

In testimony whereof I have signed my name
to this specification in the presence of two sub- 15
scribing witnesses.

LOUIS W. DILLON.
